United States Patent Office

Des. 176,871
Patented Feb. 7, 1956

176,871

PAIR OF RAIN GOGGLES OR SIMILAR ARTICLE

Walter Mantel, Floral Park, N. Y.

Application May 17, 1955, Serial No. 36,051

Term of patent 7 years

(Cl. D57—1)

Fig. 2

Fig. 1

Fig. 3

Fig. 5

Fig. 4

Fig. 1 is a top plan view of a pair of rain goggles, showing my new design;

Fig. 2 is a side elevational view thereof;

Fig. 3 is a rear elevational view thereof, with the strap omitted;

Fig. 4 is a front elevational view thereof; and

Fig. 5 is a longitudinal cross sectional view thereof taken through the center of the goggles.

I claim:

The ornamental design for a pair of rain goggles or similar article, as shown.
